UNITED STATES PATENT OFFICE.

WILLIAM C. BOWLEN, OF PROVIDENCE, RHODE ISLAND, ASSIGNOR TO
ROCKFORD SILVER PLATE COMPANY, OF ROCKFORD, ILLINOIS, A
CORPORATION OF ILLINOIS.

DESIGN FOR A HANDLE FOR SPOONS, FORKS, OR SIMILAR ARTICLES.

No. 38,656.

Specification for Design.

Patented July 9, 1907.

Application filed May 14, 1907. Serial No. 373,680. Term of patent 3½ years.

To all whom it may concern:

Be it known that I, WILLIAM C. BOWLEN, a citizen of the United States, residing at Providence, in the county of Providence and State of Rhode Island, have invented a new, original, and ornamental Design for a Handle for Spoons, Forks, or Similar Articles, of which the following is a specification, reference being had to the accompanying drawing, forming part thereof.

The figure is a plan or front view of a handle for spoons, forks, or similar articles, showing my new design.

I claim:

The ornamental design for a handle for a spoon, fork, or similar article, as shown.

WILLIAM C. BOWLEN.

Witnesses:

GEO. H. REMINGTON,
HENRY P. STONE.
